ECCENTRICALLY PROPELLED SKOOTER

John Chapman, Tuscola, Ill., assignor of one-half to Clark A. Fullerton, Tuscola, Ill.

Application July 9, 1936, Serial No. 89,861

1 Claim. (Cl. 208—38)

This invention relates to a skooter and it aims to provide a novel construction wherein a person standing thereon may, through the shifting of the weight of his body cause propulsion of the skooter, and more specifically, to provide a skooter with an eccentric connection between the body or board thereof and the propelling wheel.

The more specific objects and advantages will become apparent from a consideration of the description following taken in connection with accompanying drawing illustrating an operative embodiment.

In said drawing:—

Figure 1 is a view of the improved skooter in side elevation;

Figure 2 is an inverted plan view thereof;

Figure 3 is a front elevation, and

Figure 4 is a detail section taken on the line 4—4 of Figure 1.

Referring specifically to the drawing wherein like reference characters designate like or similar parts, the skooter is provided with a body at 10, of any suitable material, preferably somewhat elongated as shown. Adjacent the front of the skooter and beneath the same, an axle 11 is secured to an upright steering post 12 and equipped with a pair of ground wheels 13, suitably journaled on the axle. The upper end of steering post 12 is provided with a handle bar 12a.

A ground wheel 14 is provided at the rear of the board being the propelling wheel which has a central disc or body structure 15 through which an axle or bolt 16 loosely passes and is journaled. It will be noted that the bolt 16 is disposed eccentrically of the rear wheel 14 and that it is detachably connected in arms 17 by means of nuts 18 on the axle. The arms 17 are preferably angle iron, disposed in spaced apart parallel relation and bolted as at 20 to the rear end portion of the board 10.

A fender 21 may be disposed over the rear wheel 14, having its forward end fastened as at 22 to the board 10 and having its rear position supported by a U-shaped bracket 23 straddling the wheel and bolted as at 24 to the arms 17.

The previously mentioned connection 12 comprises a handle bar, rigid with the axle and journaled at 25 in the board 10, extending to any suitable height for operation. Undue swing movement of the axle 11 is prevented by abutment thereof with stops as at 26 and to permit

maximum movement of the wheels 13, the body is preferably notched at its sides as at 27.

A suitable bracket 28 is bolted at 29 to the body or board 10 and fastened to the top thereof as at 30 is a fender or shield 31 preferably extending over the front wheels 13, it being clear that the shield 31 has an opening therethrough through which the steering post 12 passes.

The wheels 13 and 14 are preferably of the pneumatic tired type.

In operating the vehicle the rider starts the device and stands on the forward end of the board or body 10, grasping the ends of the handle bar 12a. The weight of the rider will cause the wheel 14 to rotate because of the eccentric connection of the bolt at 16 with the arms 17, the rider shifting his weight to his toes during the upward and forward movement of the eccentric connection, and back on his heels during the downward and rearward movement thereof. It has been found in practice that this action of shifting the weight of the body forwardly and rearwardly will tilt the board 10 at one end and then the other, causing the eccentric means to operate the wheel 14 and thus propel the skooter.

Movement or propulsion of the skooter is readily braked by shifting the body rearwardly a distance sufficient to prevent rising of the body at the rear end under the load of the occupant, thereby arresting motion.

Various changes may be resorted to provided they fall within the spirit and scope of the invention.

I claim as my invention:—

A skooter of the class described having a body, ground wheel means therefor, arms extending rearwardly from the body, a second ground wheel means, an axle eccentrically connecting the arms and second ground wheel means, said first mentioned ground wheel means comprising two wheels and an axle, and a handle bar rising from the axle and pivotally mounted in the body, a bracket on the body, a shield mounted by the bracket extending across the said wheels and through which the handle bar rises, a U-shaped bracket secured to said arms, and a fender secured to the last mentioned bracket and disposed over the second ground wheel means.

JOHN CHAPMAN.
